(57) **CLAIM**

The ornamental design for an electronic device, as shown
and described.

DESCRIPTION

FIG. 1 is a front elevation view of an electronic device,
showing our new design;

FIG. 2 is a rear elevation view thereof;

FIG. 3 is a right side elevation view thereof;

FIG. 4 is a left side elevation view thereof;

FIG. 5 is a top plan view thereof; and,

FIG. 6 is a bottom plan view thereof.

The electronic device is intended, for example, to generate
electric simulation signals, to stimulate one or more anatomical
structures, such as the spinal cord.

The broken lines of even length shown in the drawings
illustrate portions of the electronic device that form no part
of the claimed design.
